UNITED STATES PATENT OFFICE

171,037

AQUARIUM

Harold V. Lee, College Point, N. Y.

Application February 24, 1953, Serial No. 23,755

Term of patent 3½ years

(Cl. D91—2)

To all whom it may concern:

Be it known that I, Harold V. Lee, a citizen of the United States, residing at College Point, Long Island, county of Queens, State of New York, have invented a new, original, and ornamental Design for Aquarium, of which the following is a specification, reference being had to the accompanying drawing, forming a part thereof, and wherein—

Figure 1 is a side elevational view, and

Figure 2 is a top plan view of an aquarium, showing my new design.

The design for the aquarium disclosed resides in specific ornamentation on the one side as shown.

I claim:

The ornamental design for an aquarium, substantially as shown and described.

HAROLD V. LEE.
